DISPENSER FOR LIQUID SOAP OR THE LIKE

Selwyn Ancel, River Forest, Ill., assignor to Madison Chemical Corporation, Maywood, Ill., a corporation of Delaware

Filed Dec. 18, 1968, Ser. No. 15,044

Term of patent 14 years

Int. Cl. D6—01

U.S. Cl. D33—30

FIG. 3

FIG. 5

FIG. 6

FIG. 1

FIG. 2

FIG. 4

FIG. 7

FIG. 1 is a front elevational view of a dispenser for liquid soap or the like showing my new design;

FIG. 2 is a side elevational view thereof;

FIG. 3 is a top plan view thereof;

FIG. 4 is a bottom plan view thereof;

FIG. 5 is a fragmentary cross sectional view taken on line 5—5 of FIG. 3;

FIG. 6 is a cross sectional view taken on line 6—6 of FIG. 5; and

FIG. 7 is a fragmentary cross sectional view taken on line 7—7 of FIG. 4.

I claim:

The ornamental design for a dispenser for liquid soap or the like, substantially as shown.
